UNITED STATES PATENT OFFICE.

FRANCIS JOSEPH JAMES GIBBONS, OF WOLVERHAMPTON, ENGLAND.

METAL WINDOW FRAME AND SASH OF THE SLIDING-SASH TYPE.

1,345,669.

Specification of Letters Patent.

Patented July 6, 1920.

Application filed February 26, 1919. Serial No. 279,394.

To all whom it may concern:

Be it known that I, FRANCIS JOSEPH JAMES GIBBONS, subject of the King of Great Britain, residing at St. John's Works, 5 Church Lane, Wolverhampton, in the county of Stafford, England, have invented new and useful Improvements in Metal Window Frames and Sashes of the Sliding-Sash Type, of which the following is a specification.

This invention relates to metal window frames and sashes of the horizontally sliding sash type and its object is to permit access to the outer surface of the sliding sash 10 for cleaning.

To achieve this object the invention consists in a construction whereby the sliding sash when slid open becomes pivoted vertically so that it can be turned inward to provide ready access to its outer surface from 15 the inside of the building.

For this purpose means are provided to pivot the sliding sash vertically, directly on the window frame, when over a lateral portion 20 of the window frame and simultaneously to permit same to leave the guides on which it slides, from which it is previously precluded from leaving.

A constructional embodiment of the invention is illustrated on the accompanying drawings, in which:—

Figure 1 is an inside front elevation showing the sash closed,

Fig. 2 is a similar view showing the sash 35 slid open to the right,

Fig. 3 is a sectional plan showing the sash partly slid open, and in dotted lines, the sash fully slid open and partially swung inward,

Fig. 4 is a vertical section on a larger scale of the frame with the sash slid open.

a is the fixed window frame and *b* the sliding sash.

The sash *b* is held against the frame *a* and is guided when sliding by studs *c* and segments *d* protruding vertically at the top and bottom, which engage in channels *e* provided in the frame *a*. Also a flange *f* on the top and bottom of the sash *b* engages on the inner side of the inner flange *g* of each channel *e*.

When the sash is fully slid open over the right hand lateral portion of the window frame, the studs *c* and segments *d* register 55 with the notches *h*, *i* formed in the flanges *g* of the channels *e*, and at the same time

pivots *j* protruding vertically at the right hand border of the sash *b* have entered, through slotways *k*, into pivot holes or eyes *l* in brackets secured to the fixed frame *a*. 60 The sliding sash *b* is thereby free to be swung inward on these pivots, as shown in dotted lines in Fig. 3.

Owing to the slotways *k*, at the commencement of the inward swing of the sash *b* the brackets cannot hold the pivots *j* to preclude the sash *b* from tilting edgewise, hence the segments *d* are provided at the pivot edge of the sash *b* instead of simple studs, to afford a sufficient length of surface, especially at the top of the sash, to bear against the flanges *g* at the respective side of the notches *i*, to support the sash until swung farther inward. The pivots *j* of the sash are of oblong section with the long 75 dimension in the plane of the sash and equal to the diameter of the holes *l*, which are circular, and the narrow dimension such as to pass along the slotways *k*. Consequently on swinging the sash inward the 80 long dimension of the section of the pivots *j* becomes oblique to the slotways *k* and the pivots *j* are retained in the eyes *l* of the brackets.

m is a casement fastener for holding the 85 sash *b* in its closed position.

n is a weather strip.

Although in the illustrated example, owing to the left hand portion of the frame being in the plane of the sash *b*, the latter 90 can slide to the right hand side of the frame only, it will be understood that with a window frame wholly out of the plane of its sliding sash, the latter could be arranged to slide and be fitted to pivot on both left 95 and right sides of the frame, the brackets being duplicated and, if desired, the pivots also.

I claim:

1. A metal window frame, having a window aperture and a portion lateral to said aperture, a metal horizontally sliding sash normally covering said aperture and means automatically releasing said sash directly from and automatically causing said sash 100 to become directly pivoted on said frame when said sash is slid open away from said aperture and over said lateral portion of said frame.

2. A metal window frame having a window aperture and a portion lateral to said aperture, a metal horizontally sliding sash 110

- normally covering said aperture, notched guide flanges and slotted eyed brackets on said frame, projections on said sash normally engaging said flanges and pivots on said sash, said projections registering with the notches of said flanges and said pivots entering said brackets when said sash is slid open away from said aperture and over said lateral portion of said frame.
- 10 3. A metal window frame and metal horizontally sliding sash, notched guide flanges on said frame, studs and segments on said sash engaging said flanges and registering with the notches thereof when said sash is slid open, slotted eyed brackets on said frame and pivots on said sash adjacent to said segments and entering said brackets when said sash is slid open.
- 15 4. A metal window frame and metal horizontally sliding sash, notched guide flanges
- on said frame, projections on said sash engaging said flanges and registering with the notches thereof when said sash is slid open, slotted eyed brackets on said frame and pivots of elongated section on said sash 25 entering said brackets when said sash is slid open.
5. A metal window frame and metal horizontally sliding sash, notched guide flanges on said frame, studs and segments on said sash 30 engaging said flanges and registering with the notches thereof when said sash is slid open, slotted eyed brackets on said frame and pivots of elongated section on said sash adjacent to said segments and 35 entering said brackets when said sash is slid open.

In testimony whereof I have signed my name to this specification.

FRANCIS JOSEPH JAMES GIBBONS.
